Joyce Curry, Suitland, Md. (2300 S. 24th Road, Apt. 730, Arlington, Va. 22206), and Martha G. Pugh, 11 New Providence Ave., Summit, N.J. 07901

Filed Apr. 2, 1971, Ser. No. 130,867

Term of patent 14 years

Int. Cl. D2—02

U.S. Cl. D2—29

FIG. 2

FIG. 1 is a front perspective view of an ensemble including blouse and panty hose showing our new design, the other side of the panty hose portion being conventional; and

FIG. 2 is a rear perspective view of the blouse portion of the design.

We claim:

The ornamental design for an ensemble including blouse and panty hose, as shown and described.
